UNITED STATES PATENT OFFICE.

ANDREW C. HELMICK, OF HAVILAND, KANSAS.

CORN HUSKER.

1,413,025.

Specification of Letters Patent. Patented Apr. 18, 1922.

Application filed October 17, 1921. Serial No. 508,224.

To all whom it may concern:

Be it known that ANDREW C. HELMICK, a citizen of the United States, residing at Haviland, in the county of Kiowa and State 5 of Kansas, has invented certain new and useful Improvements in Corn Huskers, of which the following is a specification.

This invention has relation to certain new and useful improvements in a corn husker 10 of the type which may be readily clamped upon the wrist or forearm and by the use of which the work of husking corn may be performed more speedily and will be made much easier for parties undertaking this 15 work.

The invention has for an object the provision of a corn husker which may be of extremely simple construction and operation and composed of the minimum number of 20 parts.

The invention has for a further object the provision of a corn husker of the character stated which will be of simple operation, highly efficient in use and will be formed 25 for attachment to the wrist or forearm in such a manner as to be securely held thereon and still leave the hand of the operator free.

The invention has for a still further object the provision of a corn husker of the 30 character stated in which will be provided a pair of opposed resiliently mounted husking or husk engaging and tearing members which will operate automatically to engage and tear the husks and then return to normal position ready for the next operation.

With the foregoing and other objects in view as will appear as the description proceeds, the invention consists in the novel construction, combination and arrangements 40 of co-operating elements as hereinafter more specifically set forth, claimed and shown in the accompanying drawings forming a part of the present application and in which:—

Figure 1 is an elevation of the corn husker, 45 showing the same applied to the forearm, the forearm being indicated by dotted lines.

Figure 2 is an enlarged plan of the corn husker removed and showing the straps extended.

Figure 3 is a detail transverse section on the plane of line 3—3 of Fig. 2, looking in the direction indicated by the arrows.

Referring more in detail to the drawings in which similar reference characters designate corresponding parts throughout the 55 several views, 1 indicates the flexible body,

which may be constructed of several pieces, as indicated in the drawings and is preferably composed of leather or some other suitable material which may be placed comfortably against the arm and supported thereon by a plurality of flexible securing members, such as perforated straps, as shown in Figs. 1 and 2 and which may be readily extended around the forearm and secured in buckles 60 3 or other suitable securing members. The straps 2 are shown as extending from one side of the body 1 while the buckles 3 are located on the opposite side portions of the body 1. A supporting plate 4, preferably of 65 arcuate form or transversely curved, as shown in Fig. 3, is secured by suitable securing members 5 to the outer face of the body 1, as illustrated in the drawings. This plate 4 is curved transversely to conform 70 to the curvature of the arm so that the corn husker may be comfortably mounted thereon.

Secured upon the central portion of the plate 4 and extended transversely thereof, are a pair of supporting and bracing plates 80 6, which have their opposed edges turned outwardly to form the base flanges 7 extended transversely of the plate 4. A spring supporting plate 8 is secured to the plate 4, between the flanges 7 and the ends of this plate 85 8 project past the ends of the flanges 7, as shown in Figs. 2 and 3. Springs 9 are mounted on the outer ends of said plate 8 with one end of the springs bearing thereagainst, while the opposite or outer ends of 90 the spring 9 bear against outwardly turned arms 10 of the husking hooks or husking fingers 11. These husking fingers 11 are pivoted at their inner ends, as shown at 12 in supporting bearings 13 secured between 95 the end portions of the flanges 7. These supporting bearings 13 have converging stop walls 14 at their inner sides to limit movement of the husking fingers 11 toward one another, under influence of the springs 100 9. The husking fingers 11 have their outer or operating ends extended outwardly and diverging, as shown at 15, then bent upon themselves, as shown at 16 and extended inwardly to form the converging and 105 pointed finger ends 17, practically parallel with the outwardly diverging portions 15, of the fingers 11. The free pointed ends 17 of the fingers 11 terminate just outwardly of the point at which the fingers 11 have 110 their converging and diverging portions meeting. Each husking finger 11 is also

preferably formed of a single section of suitable material, bent as above described. Attention may also be directed to the fact that this member is preferably bent around its pivot 12 before being brought back upon itself and then extended outwardly to form the arm 10 thereof.

It is believed that the complete construction and operation of this device may now be apparent from the foregoing paragraphs taken in connection with the accompanying drawings and the operation may be briefly stated as follows. After the husker has been secured upon the arm, as illustrated in Fig. 1, with the curved or central portion thereof preferably against the inner side of the arm, the husker may be readily used without interfering with the free movement of the hand. The hand and arm are operated in such a manner as to force the husking fingers 11 away from one another as they pass on opposite sides of the ear of corn, until a portion of the ear is enclosed between the inner or main sections of the husking fingers 11. A movement of the arm in the reverse direction to draw the same away from the ear of corn, will then cause the working ends 17 of the husking fingers 11 to grip and tear into the husk of the ear and separate the same from the ear, the springs 9 serving to constantly exert a pressure upon the arms 10 of the husking fingers 11 and thereby force the working ends 17 of the fingers 11 toward one another. As the corn husker is withdrawn from the ear, the husking fingers 11 return automatically to normal or unoperated position, ready for the next operation.

While the preferred embodiment of the invention has been shown and described, it will be understood that minor changes in the details of construction and arrangement of parts may be resorted to within the scope of what is claimed without departing from the spirit of the invention.

What I claim is:—

1. A corn husker comprising a supporting plate, means for securing said supporting plate to the arms, a pair of opposed husking fingers pivotally mounted on said supporting plate, said husking fingers having inwardly turned working ends, and means for normally forcing said working ends towards one another.
2. A corn husker comprising a supporting member, means for securing removably the

supporting member to the operator's arm, a pair of inwardly directed husking fingers pivotally mounted upon said supporting member, the working ends of said fingers being directed toward one another, and means for resiliently retaining said husking fingers in one position.

3. A corn husker comprising a supporting member, means for removably mounting said supporting member upon the operator's arm, a pair of converging husking fingers pivotally mounted on said supporting member and having working ends directed toward one another, means for resiliently forcing said husking fingers toward one another and means for limited movement of said husking fingers toward one another.

4. A corn husker comprising an arcuate supporting member, means for securing removably the supporting member upon the operator's arm and spacing said member from the arm, supporting members carried on said supporting plate, husking fingers pivotally mounted between said supporting members and limited in their movement toward one another, the outer portions of said husking fingers being extended outwardly in diverging relation to one another and then turned inwardly and terminating in pointed working ends spaced from one another and from the main portions of the respective fingers, said husking fingers having outwardly turned arms adjacent their inner ends, and means engaged with said last mentioned arms to resiliently force said husking fingers toward one another.

5. A corn husker comprising a flexible member adapted to be removably secured upon the operator's arm, an arcuate supporting plate secured upon the outer face of said flexible member, rigid supporting members carried on the outer face of said supporting plate, husking fingers pivotally mounted in spaced relation between said supporting members, means provided for limiting inward movement of said husking fingers toward one another, said husking fingers having their outer ends terminating in inwardly directed and pointed operating ends spaced from one another and from the respective fingers, thereby providing the ear receiving pocket inwardly of the working ends of said fingers, and means to resiliently force said husking fingers toward one another.

In testimony whereof I affix my signature.

ANDREW C. HELMICK.
